TIMING DEVICE

Gustav F. Gerdts, Bremen, Germany

Application May 5, 1937, Serial No. 140,829
In Germany May 26, 1936

7 Claims. (Cl. 161—15)

This invention relates to an indicating device and refers more particularly to a time indicator used in conjunction with boiler valves, which remove mud, silt, sludge and other deposits from steam boilers.

Valves of this type are usually operated very often, namely, every hour or every two hours, and remain open for a short time, mostly two to three seconds. The reason for this manner of operation is that mud, silt or deposits should be removed from the steam boiler shortly after they have been brought thereto, while they are still loose and flaky and are carried by the water flowing within the boiler; on the other hand these sediments should be removed without causing a considerable loss of water and heat, which would make the use of the deposit-removing valves unprofitable and even dangerous.

The valves are now operated by hand and require considerable work and attention on the part of the workmen. Since an improper handling of the valves may cause great damage, many plants have found it necessary to employ special supervisors for controlling the workmen in charge of the valves.

These valves are sometimes combined with a counting device or a clock, which indicates the number of times a valve has been operated in the course of one day or the time of the opening of the valve. Up to now, no devices were constructed which would indicate the period of time during which the valve was opened, although this information is of considerable importance to the operator. The determination of this period was left to the discretion or skill of the operator and in case of an accident it was impossible to find whether the damage was caused by the valve being kept open for a too long or a too short period of time. Furthermore, it was difficult, if not impossible to keep the valves open for equal periods of time, or to correct the manner of operating a valve, if it was found that in the past the time periods during which the valve was open, were too long or too short.

An object of the present invention is the provision of a valve-indicator, by means of which the workman in charge of the operation of the valves can easily determine the correct time interval during which a valve should remain open.

Another object is to provide a timing device which is combined with a valve mechanism, and which would make it possible for the engineer or the supervisor to determine whether the valve mechanism has been properly operated.

The above and other objects of the present in-

vention may be realized through the provision of a device, which is connected with a valve and which may comprise a wound clock-work mechanism, a hydraulic brake mechanism, or the like, operated by means movable along with the valve lever. The clock-work mechanism or the hydraulic device may be connected to an indicator of the usual type and may be provided with a seconds' hand, movable over a dial while the valve remains open.

The same device may operate a warning signal, such as a disk, at the expiration of a predetermined period of time during which a valve is to remain open. This warning disk may be so constructed that when the valve is closed, it is moved back out of sight, either by its own weight, or under the action of a spring.

If for some reason the operator did not close the valve after the appearance of the warning signal, then a second signal, such as a red disk, takes the place of the first disk. This second disk may be so constructed, that it will not move back automatically into its original position after the valve has been switched off, thus indicating to the supervisor or the engineer, that the valve remained open for a too long a time.

The invention will appear more clearly from the following detailed description when taken in connection with the accompanying drawings, showing by way of example preferred embodiments of the inventive idea.

In the drawings:

Figure 1 is a diagram showing a valve combined with a clock-work mechanism.

Figure 2 is a diagram showing a valve combined with a hydraulic device.

The device shown in Figure 1 of the drawings comprises a boiler-valve 60, which is carried by a pipe 61, and which is operated by a lever 63.

The mechanism, by means of which a downward movement of the lever 63 causes the opening of the valve 60, is of standard type and is not further shown in the drawings. As soon as the valve 60 is opened, mud, silt and other impurities contained in the water of a steam boiler, will be removed along with some of this water through the pipe 61.

One end of a cord 3 is passed through the opening 64, provided in the lever 63, and is firmly connected with this lever. Obviously the cord 3 may be replaced by a wire, a rod or any other suitable connecting means.

The opposite end of the cord 3 is carried by a hook 4, which is screwed into the lower end of a vertical rod 6. The rod 6 is reciprocable

in a casing 8, which is indicated diagrammatically in the drawing and which is provided with a lower chamber 65 and an upper chamber 66. The lower end of the rod 6 has the form of a 5 disk 13, which is situated within the chamber 65 and which is of larger diameter than the diameter of the opening 5, connecting the lower chamber 65 with the upper chamber 66.

A coiled spring 12 is situated within the 10 chamber 65 and surrounds the cord 3. The lower end of the coiled spring 12 presses against the bottom of the chamber 65, while its upper end is in engagement with the disk 13.

The movable rod 6 extends through the chamber 66 and is provided with an opening or slot 7. A rod 15, the operation of which will be described hereinafter, extends through the opening 67, provided in the casing 8 as well as through the opening 7 of the rod 6. A clock-work spring 20 17 presses the rod 15 downward against the bottom wall 68 of the opening 7. The upper end of the spring 17 is firmly connected with the lever 15, while its lower end is attached to a casing 69, which may constitute an integral part 25 of the casing 8.

The upper end of the rod 6 is connected by a link 9 with a tracer or pen 70, which is movable over a paper dial of the recording disk 10. The disk 10 is rotated by means of a clock-work mechanism 11, which is diagrammatically indicated in the drawings.

The lever 15 is integral with a disk 71, which is rotatably mounted upon a pivot 16. A toothed segment 14 which is also integral with the disk 71, is situated opposite the lever 15.

The teeth of the segment 14 mesh with the teeth of a gear 18, which is rotatably mounted upon a shaft 71, and which is firmly connected and rotatable along with a larger toothed wheel 40 19. The teeth of the wheel 19 are in engagement with the teeth of a gear 20.

The gears 18, 19 and 20 constitute a typical gear drive of the usual clock-work mechanism which also contains other gear wheels not shown in the drawings. The last wheel of the clock-work mechanism is in engagement with an escapement wheel 24 cooperating with its escapement 25 which serves as a brake and balancing weights 26 which may be so adjusted that the 50 clock-work mechanism can run for a predetermined period of time.

The wheel 24 carries a tooth or cog 28, which is in engagement with the teeth of a ratchet wheel 22.

55 The wheel 22 is firmly connected with a hand or indicator 21, movable over the scale 27.

Another gear 28 is also in engagement with the gear 19 and carries two curved pieces 29 and 30. The pieces 29 and 30 are adjustably mounted 60 upon the wheel 28 and are rotatable therewith. The wheel 28 is rotatably mounted upon a shaft 72.

Two disks 32 and 38 are situated one over the other, the disk 38 being preferably red in color. The disk 32 is carried by a rod 31, while the disk 38 is carried by a rod 37. The lower ends of these rods are mounted upon a pivot 33, which is carried by a casing 36. The rod 31 is also firmly connected, or made of a single piece with another rod 73, the free end of which carries a weight 35.

The casing 36, which is indicated diagrammatically in the drawings, is provided with a 75 small window 34, which is so located that the

disks 32 and 38 may be moved in front of this window.

The device operates as follows:

In the position shown in Figure 1, the valve 60 is closed; the clock-work mechanism 11 will 5 slowly rotate the disk 10, while the clock-work mechanism 19 to 24 will be at a standstill. In this position the spring 12 presses the disk 13 against the top wall of the chamber 65 and the lever 15 is pressed upward by the surface 68 of the rod 10 6, so that the spring 17, which is weaker than the spring 12, is expanded.

When the operator desires to open the valve 60 he presses the lever 63 downward, which will move along with the cord 3. Since the cord 3 15 is connected by means of the hook 4 with the rod 6, the rod 6 will also move downward along with the disk 13, thereby compressing the spring 12. The link 9 also moves downward along with the rod 6 and actuates the pen 70, which will indicate 20 upon the disk 10 the time at which the opening of the valve took place; furthermore, the line drawn by the pen 68 will show whether the valve was open to the full extent or only partly.

The lever 15 will not move downward along 25 with the rod 6, in spite of the pulling action of the spring 17, due to the engagement of the teeth of the segment 14 with those of the gear 18. The slot 7 makes it possible for the rod 6 to move independently of the lever 15.

However, as soon as the surface 68 of the rod 6 is moved out of contact with the lever 15, the spring 17 will begin to operate as the spring of a 30 clock-work mechanism, causing a slow rotation 35 of the lever 15 and the segment 14 around the pivot 16.

Since the teeth of the segment 14 engage those of the gear 18, the rotation of the segment 14 will be transmitted to the gears 18, 19 and 20, other gear wheels not shown in the drawings, the 40 escapement wheel 24 and the ratchet wheel 22. The hand 21 attached to one of the gear wheels, will move slowly over the scale 27 indicating the 45 number of seconds elapsed since the opening of the valve 60.

Since the wheel 19 meshes with the wheel 28 this latter wheel will be rotated by the wheel 19. The curved pieces or projections 29 and 30 upon the wheel 28 are so selected that after a predetermined time from the moment of the opening 50 of the valve the curved piece 29 will turn the rod 31 and the disk 32 connected with it around the pivot 33 to such an extent that the disk 32 will appear in front of the window 34 provided in the casing 36.

As shown in Figure 1, the second curved piece 30 is so spaced from the curved piece 29, that it will come into contact with the rod 31 after the disk 32 has been moved by the piece 29. The disk 38 is situated between the disk 32 and 60 the window 34. When, finally, the disk 38 is moved by the piece 30 in front of the window 34, covering the disk 32, the operator will know that the valve 60 has been maintained open for an undesirably long period. The disk 32 is provided with the counterweight 35, so that it will move back into its original position shown in Figure 1, as soon as the piece 29 is moved out of contact with the rod 31. However, the disk 38 has no counterweight, so that it will remain 70 in front of the window 34 even after the valve 60 has been closed, thereby serving as an indication to the inspector or foreman that the valve has been improperly operated.

When the operator releases his pressure upon 75

- the lever 63 of the valve 60, the lever 63 will return into its original inoperative position due to the action of a spring (not shown) or the steam pressure in the boiler, thereby closing the valve.
- 5 Then the rod 15 and the toothed segment 14 will be moved back to the position shown in Figure 1, by the rod 6 thereby rotating the gears of the clock-work mechanism in opposite directions and expanding the spring 17. The wheel 10 28 will rotate along with the wheel 19, thereby moving the pieces 29 and 30 out of engagement with the rods 31 and 37, respectively. As already mentioned, the weight 35 will swing back the disk 32. At the same time the pen 70 will be also 15 brought into the position shown in Figure 1 by the rod 6. However the cog 23 engaging the wheel 22 will prevent the wheel 24 and the escape- 20 ment 25 from participating in this return move- 25 ment.
- 20 In the device shown in Figure 2, hydraulic means are used instead of the clock-work mechanism, similar parts being designated by the same numerals. The arm 63 of the valve 60 is connected by a cord 3 and a hook 4 with the rod 6, 25 having a disk 13 which is in engagement with the spring 12. The rod 6 is provided with a slot 7, through which the bar 39 extends. The upper end of the rod 6 is connected by means of a link 9 with a pen 70 adapted to trace lines 30 upon the disk 10, operated by a clock work mechanism 11.

The bar 39 is firmly connected with a piston rod 46 carrying a piston 47. The piston 47 is situated within a cylinder 48 provided with a cover 80. The cylinder 48 is filled with oil 49, or any other suitable liquid.

The piston 47 is provided with a narrow passage 51 extending through the piston, and is also provided with a non-return valve 50, having a disk portion 81, adapted to fit into a suitable recess provided in the piston. The valve 50 is also provided with a conical rear portion 82 having an opening, which constitutes a continuation of the opening 83, surrounding the valve 50.

45 The bar 39 is provided with an upper portion or rack 41, having teeth 84, which are in engagement with the toothed wheel 43 firmly connected with an indicator or hand 44, and rotatably mounted upon a pivot 85. The hand 50 44 is movable over a scale 45. The rack 41 is guided by a casing or guide 42, which is connected with a casing 86.

The upper end of a compression spring 40 is attached to the casing 86, while the lower end of 55 this spring presses against the bar 39.

The device operates as follows:

When the lever 63 of the valve 60 is moved downward, the cord 3 attached to the hook 4 moves the rod 6, thereby actuating the pen 70 60 which will indicate the time of the opening of the valve 60 and the extent to which the valve has been opened.

Since the bar 39 is situated within the slot 7 provided in the rod 6, the bar 39 will not 65 participate in the downward movement of the rod 6. However, the spring 40, which is then in a state of compression will be free now to move downward the rod 39 and the piston rod 46, connected therewith.

70 Since the rack 41 is guided by the casing 42 the pressure of the compressed spring 40 will be directed directly downward and will be transmitted through the piston rod 46 to the piston 47. The piston 47 will begin to move down- 75 ward slowly and the oil will flow gradually up-

ward through the narrow passage 51. At that time the non-return valve 50 will be closed, the disc 81 of this valve being situated in the recess provided in the piston 47. At the same time the toothed wheel 43 will be slowly rotated by 5 the rack 41, thereby gradually moving the hand 44 over the scale 45.

The pressure of the spring 40 and the indicia upon the scale 45 may be so arranged that the hand 44 will operate as the second hand of a 10 clock, indicating the time interval during which the valve 60 has remained open. In order to attain this result the indications upon the scale 45 must be placed at unequal distances from each other, thereby compensating for the variable pres- 15 sure of the spring 40.

In order to close the valve 60 the operator releases the pressure upon the lever 63, which will then move to its original position shown in Figure 2. The spring 12 will expand and move 20 the rod 6 which will contact the rod 39 and move it upward along with the piston rod 46 of the piston 47. At that time the non-return valve 50 will be opened, as shown in Figure 2, so that the oil situated above the piston 47 will flow freely 25 through the opening 83 into the lower portion of the cylinder.

Since the spring 40 is weaker than the spring 12, it will be compressed in the course of the upward movement of the rod 39. The rack 41 will 30 rotate the toothed wheel 43, moving the hand 44 back into its original position.

What is claimed is:

1. A time indicating device comprising an oscillatable lever, a toothed segment connected with 35 said lever and movable therewith, a time hand, a clock mechanism operatively connecting said time hand with said segment and comprising an escapement wheel, an escapement adapted to engage said escapement wheel, and balancing 40 weights carried by said escapement; means connected with said lever for moving it from a predetermined position when a valve is opened, said movement of the lever being transmitted by said segment and said clock mechanism to said time- 45 hand, whereupon said time-hand is actuated by said clock mechanism, and means adapted to engage said lever and move it back into said predetermined position when said valve is being closed. 50

2. A time indicating device comprising a movable element, a time hand, means operatively connecting said time hand with said movable element, resilient means pressing against said movable element, a piston rod connected with said 55 movable element, a piston connected with said piston rod, a cylinder enclosing said piston, said cylinder being filled with a fluid, a narrow passage for said fluid being formed in said piston, a non-return valve carried by said piston, and 60 means engaging said movable element and holding it in a predetermined position against the pressure of the second-mentioned means when a valve is closed, the last-mentioned means releasing said movable element when said last-mentioned 65 valve is opened.

3. A time indicating device, comprising a rod having a slot formed therein, a movable elongated member extending through said slot and contacting said rod, means connected with said rod for 70 moving the same when a valve is actuated, means connected with said elongated member for causing it to follow said rod when the latter is moved, a time hand, and means operatively connecting said time hand with said elongated member to 75

move said time hand when said elongated member is moved.

4. A time indicating device comprising a bar, a rack firmly connected with said bar, guiding means for said rack, a pinion meshing with said rack, a time hand carried by said pinion, means connected with said bar for slowly moving the same from a predetermined position when a valve is opened and thereby moving said time hand, and means adapted to engage said bar for moving it back into said predetermined position.

5. A time indicating device comprising a movable element, a gear wheel, means operatively connecting said gear wheel with said movable element, means connected with said movable element for moving the same from a predetermined position when a valve is opened, said movement of the movable element being transmitted by the first mentioned means to said gear wheel, means 10 adapted to engage said movable element and move it back into said predetermined position when said valve is being closed, a casing having an opening formed therein, two warning discs 15 adapted to be moved in front of said opening, means connected with said gear wheel for moving said discs one after the other after a predetermined time interval in front of said opening, and means connected with that one of said discs which was first moved in front of said opening, for moving it back into its original position, the other one of said discs remaining in front of said opening after the valve has been closed.

6. A time indicating device comprising a movable lever, means connected with said movable

lever for moving the same from a predetermined position when a valve is opened, means adapted to engage said movable lever and move it back into said predetermined position when said valve is being closed, a wheel, means connected with 5 said wheel for driving the same, means connecting said lever with the last-mentioned means to turn said wheel when said lever is actuated, at least one projection carried by said wheel, at least one rotatable rod, and a signalling device 10 carried by said rod, said projection being adapted to engage and move said rod, whereby said signalling device is actuated.

7. A time indicating device, comprising, in combination, a rod having a slot formed therein, 15 a recording disc, means connected with said recording disc for rotating the same, a tracer situated over said recording disc, means operatively connecting said tracer with said rod, a movable elongated member extending through said slot 20 and contacting said rod, means connected with said rod for moving the same from a predetermined position when a valve is opened, said movement of the rod being transmitted by the second-mentioned means to said tracer, means 25 connected with said elongated member for causing it to follow said rod when the latter is moved, a hand, and means operatively connecting said hand with said elongated member to move said hand when said elongated member is moved, 30 whereby said hand is moved while said tracer is actuated.

GUSTAV F. GERDTS.
